Victor J. Evans
ATTORNEY.

UNITED STATES PATENT OFFICE.

PAUL VEITH, OF SAN FRANCISCO, CALIFORNIA.

DOOR-HASPB.

1,342,361.

Specification of Letters Patent.

Patented June 1, 1920.

Application filed November 29, 1919. Serial No. 341,348.

To all whom it may concern:

Be it known that I, PAUL VEITH, a citizen of the United States, residing at San Francisco, in the county of San Francisco and 5 State of California, have invented new and useful Improvements in Door-Hasps, of which the following is a specification.

This invention has reference to an improved door hasp.

10 An object of the invention is to produce a hasp which has its body portion secured on the inner face of a door so that the swinging portion thereof which carries the lock receiving bail may be passed through an opening in the abutment for the door and receive the lock, the construction and arrangement being such that when the door is locked the hasp is fully inclosed, and consequently can not be tampered with by parties 15 intent on burglarizing the structure to which the hasp and lock is attached.

A further object of the invention is to produce an improved construction of door hasps in which the attaching plate is secured 20 to the inner face of a door, and the swinging plate which carries the lock receiving bail is provided with an offset portion at its hinged connection with the securing plate, the said offset portion serving as a contact 25 member and designed to engage with the abutment for the door when the door is swung closed, so as to swing the hasp upon its pivot and cause the bail carried thereby 30 to be directed through a suitable opening in the abutment member, thus automatically 35 operating the swinging member upon the closing of the door to arrange the same flush against the inner face of the abutment member and to project the bail a sufficient 40 distance through the said abutment member to receive the hasp of a lock.

The foregoing and other objects which will appear as the nature of the invention is better understood may be accomplished by 45 a construction and operable arrangement of parts such as is disclosed by the drawings.

In the drawings:

Figure 1 is an elevation looking toward the outer edge of a door and the abutment portion of a building therefor showing the bail of the hasp projected through the abutment and a lock applied thereon.

Fig. 2 is a sectional view approximately on the line 2—2 of Fig. 1.

55 Fig. 3 is a similar sectional view but showing the arrangement of parts when the

contact member of the hasp engages with the outer edge of the abutment member to cause the swinging of the hasp to bring the bail thereof through the opening in the 60 abutment member.

Fig. 4 is a perspective view of the hasp.

Referring now to the drawings in detail, the numeral 1 designates a hinged door and 2 the member of a structure to be closed by 65 the door. As the door contacts with the member 2 when the said door is in closed position, the said member 2 will hereinafter be referred to as the door abutment member.

The abutment member 2 has its outer edge 70 at the portion thereof which is in a line with the hasp, hereinafter to be described, preferably cut at an inward inclination as indicated by the numeral 3, and received in this portion of the member 2 is the angle end 4 75 of a plate 5. The plate is secured upon the outer face of the abutment member 2 and is provided with an elongated slot 6 that registers with a similar slot or opening 7 in the abutment member. The outer end wall of 80 the slot 7 is preferably beveled or arranged at an inclination as indicated by the numeral 8.

On the inner face of the door 1 is secured the fixed plate 9 of the hasp. To the outer 85 end of this plate is hingedly secured, as at 10, the swinging member 11 of the hasp. The member 11 has a right angularly extending U-shaped bail 12 on one of the faces thereof, and the said swinging member 90 at its hinged connection with the fixed plate 9 is provided with an outwardly extending preferably curved extension 13 that provides a contact member.

The swinging member of the bail, when 95 the door is to be closed, has its contact member 13 in the path of engagement with the angle end 4 of the plate 5, and by virtue of such engagement the swinging member will be swung toward the inner face of the 100 abutment member 2, causing the bail 12 to pass through the slot 7 in the member 2 as well as the slot 6 in the plate 5, the said bail being projected a suitable distance outward of the member 2 to receive the shackle 105 14 of a lock 15.

It is thought that the foregoing description, when taken in connection with the drawings will render the construction, operation and advantages of the device perfectly clear to those skilled in the art to which such inventions appertain.

Having thus described the invention, what is claimed as new, is:—

1. In combination with a swinging member, an abutment therefor and said abutment having an opening therethrough, of a hasp including a plate fixed to the inner face of the swinging member, a second plate hingedly connected to the fixed plate, a bail on the last mentioned plate, and a contact member on the last mentioned plate at its hinged connection with the fixed plate, and said contact member adapted to engage with the outer end of the abutment member when the swinging member is closed thereon, to cause the hinged member of the hasp to be brought against the inner face of the abutment member and the bail to be projected through the opening in the said abutment.
2. In combination with a hinged door and an abutment therefor, the said abutment being provided with an opening, the outer end wall of which being arranged angularly.

larly, said abutment having its outer end provided with an inclined depression, a 25 plate secured to the outer face of the abutment having a slot therein registering with the opening in the said abutment and having its outer end arranged angularly and received in the depression of the abutment, 30 a hasp including a plate which is secured on the inner face of the door, and a second plate which is hingedly connected to the fixed plate, said last mentioned plate having an extending bail thereon, and having 35 a curved extension at its hinged connection with the fixed plate that provides a contact member designed, when the door is closed to engage with the angle end of the plate on the abutment to swing the hinged plate 40 against the inner face of the abutment and to project the bail through the openings in the said abutment and plate.

In testimony whereof I affix my signature.

PAUL VEITH.
